UNITED STATES PATENT OFFICE.

STANISLAW KIELAR, OF MILWAUKEE, WISCONSIN, ASSIGNOR OF ONE-THIRD TO
STANLEY PAWELECZYK, OF MILWAUKEE, WISCONSIN.

CUFF-FASTENER.

1,210,081.

Specification of Letters Patent. Patented Dec. 26, 1916.

Application filed July 29, 1915, Serial No. 42,553. Renewed November 21, 1916. Serial No. 132,717.

To all whom it may concern:

Be it known that I, STANISLAW KIELAR, a subject of the Emperor of Austria-Hungary, residing at Milwaukee, in the 5 county of Milwaukee and State of Wisconsin, have invented certain new and useful Improvements in Cuff-Fasteners, of which the following is a specification.

This invention relates to certain new and 10 useful improvements in cuff fasteners.

An object of the present invention is to provide a fastener in which the cuff may be either formed integral with the end of a shirt sleeve or independent thereof and in 15 which the cuff is securely held in closed folded position with liability of the same becoming loosened obviated.

A further object of the invention is to provide a closure for cuffs which eliminates 20 the present usual construction of cuff link, there being provided a pocket or keeper adjacent each end of the cuff adapted for the reception of a movable fastener.

With these general objects in view and 25 others that will appear as the nature of the invention is better understood, the same consists in the novel construction, combination and arrangement of parts hereinafter more fully described, illustrated in the ac- 30 companying drawings and pointed out in the appended claim.

In the drawings forming a part of this application and in which like designating characters refer to corresponding parts 35 throughout the several views, Figure 1 is a detail perspective view of a portion of one end of a cuff illustrating one of the keeper members for the fastener; Fig. 2 is a detail perspective view of the fastener detached 40 from the cuff, and Fig. 3 is a detail sectional view of a portion of a cuff showing the cuff and fastener in closed and locked position.

Referring more in detail to the accompanying drawing, there is shown in Fig. 1 one end of the cuff 11 having secured thereto 45 a keeper or pocket strip 12 extending longitudinally thereof and completely open at each end, the same being secured to the cuff as by suitably positioned rows of stitching 50 13, it being noted that the central por-

tion of the keeper 12 is bulged or elevated from the cuff 11 to provide a clearance for the fastening member. The keeper 12 may be formed of any suitable material but is preferably formed of material from which 55 the cuff or shirt is made, although celluloid or similar material could be utilized. As shown in Fig. 3, a keeper is provided adjacent each end of the cuff and has associated therewith a removable fastener to be 60 presently described.

The form of fastening member is more clearly shown in Fig. 2 and includes a pair of identically formed ends 18 of superposed material that may inclose a whalebone or 65 other stiffening element 18' if desired, and is provided with a freely flexible central portion 19 while the ends thereof are turned over as at 20 to provide enlargements or lugs. 70

In the operation of the device, the ends 18 of the fastening member are inserted in the keepers 12 while the lugs 20 pass through the keepers and extend beyond the edges thereof, and as shown in Fig. 3, the said lugs 75 are adapted to prevent accidental displacement of the fastening member relative to the keepers 12.

While the form of the invention herein shown and described is what is believed to 80 be a preferable embodiment thereof, it is nevertheless to be understood that various forms, modifications and arrangements of the parts may be made without departing from the spirit and scope of the invention 85 as set forth in the appended claim.

What I claim as new is:—

A device of the class described, comprising in combination with a cuff, a pair of pockets secured to the same face of the cuff 90 adjacent each end thereof and open from end to end, a fastening member including stiffened end portions and a flexible central portion adapted to have the stiffened end portions received in the pockets, and lugs 95 carried by the free ends of the fastening member adapted to slightly project beyond the inner ends of the pockets.

In testimony whereof I affix my signature.

STANISLAW KIELAR.
